CLAIM

The ornamental design for an aircraft with foldable tail as shown and described.

DESCRIPTION

FIG. 1 is a front view of an aircraft with foldable tail in an extended configuration according to our new design; FIG. 2 is a top view thereof in the extended configuration; FIG. 3 is a rear view thereof in the extended configuration thereof;

FIG. 4 is a left-perspective view thereof in the extended configuration thereof;

FIG. 5 is a right perspective view thereof in the extended configuration thereof;

FIG. 6 is a bottom view thereof in the extended configuration thereof;

FIG. 7 is a front-top-right perspective view thereof in the extended configuration thereof;

FIG. 8 is a front view thereof of the aircraft with foldable tail in a retracted configuration according to our new design; FIG. 9 is a top view thereof in the retracted configuration; FIG. 10 is a rear view thereof in the retracted configuration thereof;

FIG. 11 is a left perspective view thereof in the retracted configuration thereof;

FIG. 12 is a right perspective view thereof in the retracted configuration thereof;

FIG. 13 is a bottom view thereof in the retracted configuration thereof; and,

FIG. 14 is a front-top-right perspective view thereof in the retracted configuration thereof.

The dashed lines show portions of the aircraft with foldable tail that form no part of the claimed design.
